Gardiner & Fife, Atty.

JOEL HAYDEN, JR., OF HAYDENVILLE, MASSACHUSETTS.

Letters Patent No. 83,380, dated October 27, 1868.

IMPROVEMENT IN CHECK-VALVES FOR STEAM AND OTHER ENGINERY.

The Schedule referred to in these Letters Patent and making part of the same.

To whom it may concern:

Be it known that I, JOEL HAYDEN, Jr., of Haydenville, Hampshire county, Commonwealth of Massachusetts, have invented a new and useful Improved Check-Valve for Steam and other Fluids and Liquids; and I do hereby declare that the following is a full and clear description thereof, reference being had to the accompanying drawings, and to the letters of reference marked thereon.

The drawing is a sectional view through my valve, showing its interior arrangement.

This invention consists in an improved combination of parts, with reference to a valve, by which a fluid flowing through the valve-opening is stopped off as soon, or soon after, the valve is opened as may be practicable for the purpose, by the pressure of the steam or other fluid or liquid.

In the construction of my invention, the device is formed of chamber E, into which the conduit C leads. Between this chamber and the outlet D is the partition A, with the valve-seat B, into which fits the valve J, conically shaped, and attached to a rod, G, which has also a cup, F, securely attached to it, and closing in between it and the sides of the chamber F.

The valve is opened by means of direct pressure

against the rod G, either to push it up from the bottom, or pull it up from the top, as may be most convenient.

The operation of this valve is as follows: When the valve is opened forcibly, by outside pressure against the rod G, the fluid passes through the valve-opening, and has a free flow from the inlet to the outlet, until the force is withdrawn from the rod G, and then the pressure of the fluid against the cup F forces it down, and with it the valve and rod G, thus closing the opening, and shutting off further supply.

Having described my invention,

What I claim as new, and desire to secure by Letters Patent, is—

The combination of the valve J, cup F, connecting-rod G, outlet D, and inlet C, with the partition A and valve-seat B between them, whereby the fluid or liquid is enabled to close the valve by its pressure against the cup, when the valve is relieved from outside force, substantially as herein described and shown.

J. HAYDEN, JR.
